UNITED STATES PATENT OFFICE.

JACOB LEVY, OF BOSTON, MASSACHUSETTS.

DEVICE FOR CUTTING PIPE.

Application filed July 16, 1924. Serial No. 726,274.

This invention relates to the art of cutting or threading pipes, such as stem pipes, water pipes etc., for proper assemblage in a pipe system, and is intended to provide a simple and compact construction in which suitable cutting tools, including both thread cutting and severing tools with their proper accessories, are operatively associated together in a frame work which forms a compact 5 motor casing so that the device is readily portable to the actual situs of the job being done.

To this end the invention comprises, generally speaking, a casing for operatively supporting a driving motor and a revoluble hollow pipe-receiving shaft combined with a revoluble head detachably secured to said shaft and carrying cutting tools so mounted as to perform their proper cutting operations upon the pipe, with means rendered operative at will to automatically shift the cutting tools relative to the center in accordance with the requirements of the work. This and other features of the invention will 20 be particularly described in the following specification and will be defined in the claims hereto annexed.

In the accompanying drawings I have illustrated a simple and convenient construction and arrangement embodying the various features of this invention, in which:

Figure 1 is a longitudinal vertical section through the hollow revoluble shaft supported in the upper part of the casing and 35 carrying the detachable head in which the cutting tools are operatively mounted.

Figure 2 is a front end elevation of the revoluble head.

Figure 3 is a detail view in front elevation 40 of one of the slide blocks or tool carriers mounted in said head.

Figure 4 is a detail view of one of the removable handles of the head.

Figure 5 is a side elevation of the complete casing and assembled head.

Figure 6 is a rear elevation of the tool-carrying head.

Figure 7 is a front elevation of the complete casing and hollow shaft in assembled 50 relation, the tool-carrying head being removed from the shaft.

Figures 8 and 9 are detail views showing the hand-controlled stop members by which the feeds of the cutting tools are governed.

Figure 10 is a horizontal section through the upward extension of the casing carrying

the hand-shiftable stop members shown in Figure 9.

Figure 11 is an enlarged longitudinal cross sectional view of a threaded pipe showing the form of cut made by the threading dies.

As the present device is particularly intended for portable use, I provide a hollow casing 1, whose front and rear ends, at their top, are formed with semi-circular bearings 60 for the reception of a revoluble shaft 5, the other half of said bearings being formed in the cover or top 2 which is detachably bolted to the main body or casing 1. The lower part of the casing forms a motor chamber 65 for receiving a small motor *o* whose shaft projects into a lateral gear chamber 3 and whose open side is closed by a removably secured plate 3^a so as to form a grease chamber to allow the transmission gears to run 70 in oil. The revoluble hollow shaft 5 through which the pipe to be machined is inserted is preferably mounted in annular bushing or bearing rings 5^b which are interposed between the semi-circular bearing 75 openings in the casing body 1 and those in the cover or top 2, as shown in Figure 1.

At its forward end the tubular shaft is provided with an interrupted outwardly projecting flange 5^a which forms attaching 80 wings by which the revoluble head is detachably secured by suitable bolts or screws to said shaft.

Around the middle portion of the hollow shaft 5 is secured a bevelled tooth gear ring 90 5^a which intermeshes with a driving pinion 5^a which is the last element of the gear train transmission leading from the motor *o* to the revoluble shaft 5. Without going into exact details as to the transmission train, it 95 will suffice to state that it will be of the reducing type so that the speed of the motor shall be geared down to an appropriate speed for the cutting head. Inside the hollow shaft I preferably provide a support 100 or guide for the inserted pipe to be operated on and this comprises, as shown, a skeleton tube 20 secured by a set screw inside the hollow shaft 5 and provided with removable bushings 21 at each end, which bushings may 105 be of any suitable internal diameter to fit different sizes of pipes to be cut.

The cutting operations which this machine is intended to perform are; first, the cutting of a thread on the pipe by means of suitable thread-cutting dies; and second, the severing or cutting off of the pipe at any desired 110

distance from the end thereof. I will first describe the construction by which the thread cutting is effected preparatory to cutting off the length of pipe.

As before explained, to the flanged front end of the revoluble hollow shaft is detachably bolted a tool-carrying head 6. As shown in Figures 1 and 2, the front face of this head is provided with parallel ribs or flanges 6^a which form tracks for two opposed slide blocks 7, each of which carries two threading dies in the form shown. These threading dies 8 are mounted in approximately radial slide ways or grooves 7^a, as shown in Figure 3, formed in each block 7 with the cutting teeth of the die projecting inwardly beyond the line of the circular aperture which is substantially concentric with the axis of the revoluble shaft. To make ample provision for setting the threading dies to different distances from the center to operate satisfactorily upon different diameters of pipe, each elongated die 8 is provided with a series of spaced holes 8^a, and the face plate of the block 7 covering these slide ways or grooves are provided with another series of holes 7^c spaced on a different gage from the gage which characterizes the spacing of the holes 8^a so that, on the vernier system, different holes in the adjustable die may be brought into registry with appropriate holes in the face plate of the carrier block 7 to secure the proper adjustments suitable for cutting the various standard diameters of pipe within the capacity or range of the machine. When the proper hole 8^a of each die is brought into registry with the proper hole 7^c to give the appropriate radial distance for the particular pipe to be cut, thumb screws 8^b are inserted through the outer hole into the registering hole in the die so that the die is thereby locked in its position of adjustment.

Were the dies to be kept in such position of adjustment so as to cut the entire thread to its full depth it would plow up an outstanding burr of metal at the point where the thread cutting ceases and this would require finishing off with a file by hand. In order to avoid this objectionable result I make provision for gradually withdrawing the dies automatically as they approach the end of the thread to be cut.

The means for preventing the formation of this burr at the end of the thread comprises die-shifting means which are rendered operative at will by the throwing in by hand of a stop member arranged in the path of the adjusting device so that, as the head revolves, the die-adjusting means, by engagement with said stop member, are operated during the last one, two or three revolutions of the head to shift the dies relative to the axis of rotation so as to gradually withdraw them toward the surface of the pipe, thereby pro-

ducing toward the end of the cutting operation a decrease in the depth, as shown in Figure 11. This is accomplished by means of feed screws 9 which pass through and have threaded engagement with projecting bosses 6^b on the face of the revoluble head and on opposite sides of the center thereof. The inner ends of these feed screws abut against the carrier blocks 7, and these two carrier blocks have their inner or opposed faces provided with recesses 7^b in which are seated helical compression springs 7^a, preferably coiled around guide pins 7^c, which normally tend to force said carrier blocks apart. The inner ends of the feed screws 9 abut against the outstanding faces of the two blocks, thereby normally maintaining the two carrier blocks in close engagement with each other. On the outer ends of said screws are secured pinions 9^a which intermesh with adjacent pinions 10 which are compounded with star wheels or turn-stiles 10^a whose arms, when engaged with the upper end of the stop member 80, are intermittently rotated and therefore cause the reverse rotation of the feed screw 9 each time that the feed screw, in its orbit, passes by the stop member 80. In consequence of this intermittent turning of the feed screws, the carrier blocks are allowed to expand apart, thereby moving the dies to a greater distance from the central axis and causing the progressive shallowing of the thread, thereby preventing the raising or plowing up of an objectionable burr of metal.

For convenience in the hand setting of the thread-cutting dies to accommodate different diameters of pipe, I provide a laterally projecting pin 8^c (Fig. 3) which, when the die is in its outermost position, is located in a recess in the face plate. This projects far enough, as shown in Figure 1, to easily manipulate the die members in order to set them at different distances from the center.

The pipe-cutting members that are used for severing or cutting off the pipe are best shown in Figures 1 and 6. Each cutting element comprises a sharp cutting disk or wheel 16, rotatably mounted in a radial slide 15 which is held in different positions of adjustment by means of a feed screw 17 provided with a thrust collar or shoulder 17^a, and having at its outer end a turn-stile or star wheel 18.

The revoluble head is provided with three such radial ways for receiving three such severing cutters, and I provide means similar to that already described in connection with the thread-cutting tools, for progressively feeding the severing cutters inward to cut through the entire thickness of the pipe wall. The turn-stiles 18, it will be observed by reference to Figure 2, are located nearer the center than the turn-stiles 10^a so that the two series of turn-stiles move in different

orbital paths in order to engage their own appropriate stop members. The stop member for the severing cutters, as shown at 16^a, comprises a vertical slide mounted in an upward extension 2^a of the casing, having a lateral projecting pin 16^b to facilitate its manipulation by the operator, and having on its opposite face two notches or recesses 16^c adapted to be engaged by spring detents 16^d, as shown in Figure 10.

The stop member 80, which cooperates with the turn-stiles 10^a for shifting the thread-cutting dies, has a similar manipulating projecting pin 80^a and has similar notches or recesses 80^b adapted to be engaged by a spring pressed detent 80^c. The shifting stop 80 for the die-cutting member is made longer so as to be drawn outwardly beyond the orbital path of the turn-stiles 10^a, while the forward stop member 16^a is made shorter and is moved inwardly to be set out of the path of its turn-stiles 18.

In practice, therefore, as the threads cutters approach the end of their travel, after having cut the necessary length of thread along the pipe, the operator, by merely pushing in the stop member 80^a, insures the gradual retraction of the thread-cutting dies away from the center to prevent burr. At about the same time or immediately following such setting of the stop member 80, the operator may raise the stop member 16^a in the path of the turn-stiles 18 so that the cutting off tools begin to advance toward the pipe. By the time the thread is finished the pipe cutters are advanced in contact with the pipe and begin the cutting operation. With each revolution of the head, each severing cutter moves one step inwardly and this operation continues until the pipe is completely severed.

In order to keep the work exposed to the cutting tools wet with oil, I provide a closed oil reservoir 11 mounted on the top or periphery of the revoluble head, as shown in Figures 1 and 2, the filling orifice of which is tightly closed by a plug 11^a. A drip pipe or oil-delivering pipe 11^b is carried down to within a short distance of the pipe being cut, and the drip or flow of oil is controlled by the regulating valve 11^c.

As the device is a comparatively small portable one for carrying around to the work, it is desirable to provide means for preventing the thrust of the motor-driven revolving head from re-acting to cause the reverse rotation of the casing itself when the pipe being cut is held in a vise which will usually be the case. I provide the casing or frame at any suitable point, say in the side wall, as shown in Figure 5, with a socket 40 in which may be inserted a threaded handle 41 adapted to be grasped by the hand to hold the casing stationary against reverse revolution in relation to the pipe anchored

in the vise. As shown in dotted lines in Figure 7, such a socket will be provided on opposite sides of the casing. The handle need not necessarily be held by the operator since, if it is allowed to rest against the bench or a block on the bench, it will act as a resisting lever to prevent rotation of the casing.

For emergency use in case of accident to the motor I have provided sockets 42 on opposite sides of the revoluble head to receive the threaded handles 41 so that the head may be turned by hand in case of need.

To facilitate the removal of one or both of the bosses 6^b, in which the stop screws 9 are threaded in order to remove the carriage blocks 7, one or both may be made with a rearwardly extending shank 6^d passing through an orifice in the rotary head and clamped in place by means of a clamping nut 6^e on the back of the revoluble head, as shown in Figure 6.

A feature of considerable practical importance is the employment of a definitely located stop shoulder on each stop screw 9 so that, by merely turning in the stop screw until the stop shoulder 9^c abuts against the boss 6^b, the thread cutting dies are easily and simultaneously adjusted to the correct innermost position concentric with the center of revolution. This construction dispenses with the necessity of having the operator exercise great care and skill in setting each one of the thread cutters to its proper gaging position to cut the required depth of thread. The accurate and easy setting or gaging of the thread-cutting dies effects a very material economy of time and requires no skill for its accomplishment.

What I claim is:

1. A device for cutting pipe, embracing in its construction a supporting frame, a revoluble hollow shaft mounted therein and provided with interiorly disposed removable pipe-supporting and centering means, a tool-carrying head secured to said shaft, a pair of opposed slide blocks mounted on said head, thread-cutting dies adjustably secured in said blocks, and means comprising outwardly thrusting springs and opposed automatically controlled screws engaging said blocks, for automatically moving said blocks apart to decrease the depth of the thread cut toward the end of the cutting operation in order to avoid formation of a projecting burr at the end of the thread, substantially as described.

2. A device for cutting threads on pipe, embracing in its construction a supporting frame, a revoluble hollow shaft provided with means for centrally supporting the pipe to be threaded, a revoluble head thereon, oppositely movable tool-carrying members mounted on said head and normally forced

apart by spring action, stop screws for limiting said movement apart, and a stop member adjustable at will to position to cause the stop screws to be intermittently turned to allow the tool-carrying members to move apart to prevent formation of a projecting burr at the end portion of the thread being cut, substantially as described.

3. A device for cutting pipe embracing in its construction a revolute head, a plurality of thread cutting die members arranged radially in said head with their cutting edges projecting toward the centrally disposed pipe to be cut, adjustable supporting blocks for said dies, said die members being provided with a plurality of spaced holes, the blocks also being provided with a plurality of differently spaced holes arranged in line with the holes in the die members, and adjusting pins insertable through any of the holes in the blocks into selected holes of the die members to provide a step by step ad-

justment for positioning the dies in relation to the work, substantially as described.

4. A device for cutting pipe embracing in its construction a revolute tool-carrying head, a series of thread cutting die members radially arranged to present their cutting edges toward a centrally disposed pipe, adjustable supporting blocks for said dies said die members and said blocks being provided with pin-receiving holes arranged in the same radial planes, the holes in the dies and in the blocks being differentially spaced to permit a complete range of adjustment, and a holding pin adapted to be inserted through a hole in the block into an appropriate hole in the die when they are brought into registry to set the die at a predetermined distance from the center, substantially as described.

In witness whereof, I have subscribed the above specification.

JACOB LEVY.
